UNITED STATES PATENT OFFICE.

WILLIAM BLASKEWITZ, OF DETROIT, MICHIGAN, ASSIGNOR TO CLAYTON & LAMBERT MANUFACTURING CO., OF DETROIT, MICHIGAN, A CORPORATION OF MICHIGAN.

GENERATOR APPARATUS.

Application filed October 6, 1926. Serial No. 139,876.

This invention relates to generator apparatus for liquid fuel burners and has to do particularly with the provision of a generating structure adapted to vaporize and supply fuel to any one of a plurality of burners as desired.

Heretofore in the manufacture and design of liquid fuel burners, particularly the type designed to be used in connection with collapsible or camp stoves, considerable difficulty has been experienced in obtaining and maintaining the proper quality of combustible fuel, and in the commercial stove structures that have been fairly successful, it has been the custom to utilize the main or central burner which has served the double function as a normal heating burner and also as a burner for heating the generator tube. It has therefore been necessary, during operation, to always maintain the central or main burner at approximately full operation in order to obtain and maintain an approximate supply and quality of vaporized fuel.

The present invention contemplates the provision of an entirely novel method of an apparatus for vaporizing the fuel and conducting the same to the various burners. More particularly, this invention contemplates the provision of a central vaporizing member which is adapted to initially receive all the fuel to be vaporized and conducted to all the burners but which main vaporizing member may be adjustably controlled to supply as large or as small a volume of fuel to the main or central burner as desired. The result of this structure is that the central burner may be increased or decreased as desired in the heating of a particular utensil, or it may be approximately shut off and one or more auxiliary burners left burning as desired.

Another object of the present invention is the provision of a multiple tube generating structure wherein the main and auxiliary generating tubes are so arranged with reference to the mixing chamber, or chambers, that a constant quality of fuel mixture is always obtainable and maintainable at any or all burners as desired with the result that an efficient blue flame is always present when any or all burners are turned on.

A further feature of the present invention has to do with the particular method

of vaporizing and conducting the fuel to the various burners wherein the fuel is supplied in a single column and preheated and then conducted in a plurality of columns which are submitted to a plurality of sources of heat before being finally mixed with the air to form a combustible fuel mixture. The structure for accomplishing this novel method comprises a simple generating tube for receiving the liquid fuel and which tube is positioned above a burner. This central tube is supplied with a plurality of smaller tubes whereby the initial column of liquid fuel, after being preheated, is conducted back past the main generating burner while still contained within the generator tube, after which it is passed through a second generator tube and subjected to the heat from an auxiliary burner, after which the thoroughly and efficiently vaporized fuel is combined with air to form a combustible mixture.

In the drawings:

Fig. 1 is a plan view of my novel generating and burner structure, showing part of the structure broken away to more clearly illustrate the method of vaporizing and conducting the gases to the various burners.

Fig. 2 is a side elevation of the structure shown in Fig. 1 and illustrating one form of mixing chamber and burner for conducting and utilizing the vaporized fuel.

Fig. 3 is a sectional view taken on line 3—3 of Fig. 1.

It will be understood that in the embodiment of my invention, as illustrated in the drawings, that the generator and burner structure may be utilized in connection with any suitable stove structure, or any other structure of similar nature requiring the use of burner elements. The structure is particularly adapted, however, to stove structures wherein the fuel supply tank and generating means are integral to form a unitary fuel supply unit which is slidable relative to the burner structure whereby to be easily collapsed within a relatively small space and to perform useful functions in the various positions of adjustment. I have not shown any particular type of frame or stove casing, but a particular type of stove structure to which the present invention is particularly applicable is that shown and described in a pending application No.

131,868, filed August 27, 1926, by William Blaskewitz, Charles F. Lambert, Clarence B. Overly and James Ironside.

Any number of burners may be utilized in embodying the present invention and in the drawings I have shown three burners which form the desired number of burners for use with a camp or similar cook stove. The main burner, or generator burner, may be designated 1, and the auxiliary burners at either side thereof may be designated 2 and 3. In burner structures of this type it is customary to utilize a suitable supply conduit for the fuel and to position this conduit over the central or main burner whereby such central burner serves to vaporize the fuel passing through the conduit and to also serve its normal function as a burner.

In the present invention I utilize such a central generating burner in such a manner to obtain all the advantages thereof without any of the disadvantages such as have been present in the prior art. Each of the burners 1, 2 and 3 are adapted to be connected to suitable mixing chambers 4, 5 and 6, respectively. As shown, these mixing chambers are provided with suitable air inlets 7 and generator inlets 9 whereby the gases issuing from the generators may be combined with air to form a combustible mixture.

The central burner 1 and the mixing chamber 4 are adapted to be connected to a suitable generating tube 8. This tube is of relatively large size and is adapted to contain sufficient liquid fuel to cause preheating of the generator and vaporization of the fuel to permit normal continuous operation before it is necessary to open the main inlet valve. This generator is provided with a suitable jet block 10 having tapered outlet orifices. The other end of the generator tube 8 is adapted to be threaded with a multiple generator head 11 which will be presently described in detail. The generator tube 8 is adapted to receive three smaller tubes 12, 13 and 14, as best shown in Fig. 3, and these tubes are preferably threaded into the generator tube 11, the central tube 12 being preferably longer and preferably slightly larger in diameter than the tubes 13 and 14. The tube 8, surrounding the tubes 12, 13 and 14, is packed with a plurality of rods 15 whereby the liquid fuel is trapped in the tube 8 and sped by capillary action towards the jet block, this function being particularly adaptable during the preheating operation, and also when the burners are shut down.

The central tube 12 is provided with a suitable valve rod 16 which extends throughout the length thereof and which is provided with a suitable wire 17 which projects through the tapered orifice in the jet

block 10. This wire in addition to being a cleaner for said orifice, is also adapted to so cooperate with said orifice as to control the opening and closing thereof when the valve rod 16 is advanced or retarded. In other words, this wire 17 is adapted to act as a valve for the jet block 10 to control the amount of gas entering the mixing chamber 4. The needle or wire 17 never completely closes the orifice in the jet block 10. The point of the wire 17 is preferably tapered as is the customary practice for forming cleaner wires for jet blocks, but this is not necessary. When the valve 28 is moved outwardly a relatively great distance, the end of the wire 17, or the tapered portion thereof, allows a large amount of fuel to pass through the jet block. When the valve 28 is moved toward closed position, the member 17 restricts the flow of fuel to the central burner.

The generator head 11 is of novel design and preferably consists, as shown, of three separate T-joints, or valve housings, for receiving the generator tube 8 and the auxiliary generator tubes 20 and 21, as clearly shown in Fig. 1. The joints, or valve housings, for the tubes 20 and 21 may be designated 22 and 23 respectively. The central valve housing of the generator head 11 is adapted to receive, in longitudinal alignment with tube 8, a connecting fuel conduit 24 which forms the connecting means between the generator head 11 and a suitable valve housing 25 which is adapted to be mounted upon a suitable fuel tank 26, and to be connected with a suitable conduit 27 extending within the fuel tank, as shown in Fig. 2.

The valve rod 16 preferably extends the full length of the generator tube 8, the conducting tube 24 and the valve housing 25, as shown in Fig. 1, and midway of its length the rod is enlarged in diameter and tapered, as at 28, to form a valve to cooperate with a suitable valve seat provided in the generator head. This valve rod 16 is further enlarged at 29 whereby to have a threaded end fit within the extension 30 of the generator head. A suitable slot 31 is preferably formed in this rod 16, as shown in Fig. 1, whereby to conduct the liquid fuel which is fed around the rod 16 past the threads 29 to a point where it may be controlled by the valve 28. It will be understood that this slot 31 may be formed either in the extension 30 for receiving the threads 29, or in the threaded part 29 of the valve rod. It will thus be obvious that when the valve rod 16 is backed away by turning the same, liquid fuel may be fed through the slot 31 past the valve 28 and into the tube 12, being thus forced into a thin annular wall between the rod 16 and the walls of the tube 12. When the valve rod 16 is

turned to closed position the valve 28 will completely shut off the supply of liquid fuel.

The generator head 11 is provided with suitable passageways 32 and 33, which connect with the conduits 13 and 14 to supply vaporized gas to the generating tubes 20 and 21. The supply of such gas from the passageways 32 and 33 into the generating tubes is controlled by the valve members 34 and 35. These valve members 34 and 35 preferably comprise a one-piece rod which has a threaded fit with the valve housings 22 and 23 and which rods are then reduced in diameter to form suitable valves, and then further reduced whereby to extend the length of the tubes 20 and 21, and which are further provided with suitable wires on the ends thereof to serve as cleaner members for the jet blocks in the auxiliary tubes 20 and 21. Suitable coil springs may be provided in the auxiliary generator tubes, as clearly shown in Fig. 1, whereby to restrict as well as to control the positive feed of the fuel by capillary action.

Suitable auxiliary generating burners 40 and 41 are preferably positioned, as shown in Fig. 1, beneath the generating tubes 20 and 21, and are connected with the mixing chambers 5 and 6, as shown in Fig. 2 whereby to be supplied with a combustible mixture of gas. These auxiliary vaporizing burners 40 and 41 not only assist in the vaporization of the fuel after it has been heated by the burner 1 but also serve to vaporize the fuel when such central burner 1 is turned low.

In operation, valve stem 16 may be actuated to admit sufficient fuel to the generator tube 8 as to fill the same whereupon such valve may be then closed. This entrapped fuel in the tube 8 may be preheated by any suitable means such as the priming pan, or the combined preheater and mixing chamber, as disclosed in the copending application No. 131,868. After substantially all of the entrapped fuel in this primary generating tube 8 has been vaporized by the pre-heating flame, or blast, the valve 28 may be opened to admit fresh liquid fuel to the annular space provided in the tube 12. Such fuel will be vaporized upon striking the hot surfaces of the tube 12 and the tube 8, and vaporized gas may then be fed into the primary or middle mixing chamber 4 to be mixed with a suitable supply of air to form a combustible mixture. This combustible mixture may be fed to the central burner 1 where it may be ignited and part of the resulting flames directed against the main generating tube 8 to maintain vaporization. If it is only desired to utilize the central burner for cooking or heating purposes, the valves 34 and 35 will remain closed and the valve stem 16 open to such an extent that the wire valve stem 17 will permit the de-

sired amount of fuel to enter the mixing chamber 4 and the central burner 1, whereby the flames of such central burner will not only serve as a generator heater but also for any desired heating or cooking purposes. 70 In spite of the fact that the other two burners 2 and 3 are turned off there will be no yellow flames or extreme gas pressure at such central burner, but such central burner can be regulated just as desired. 75

If it is desired to operate either one or both of the burners 2 and 3 it is only necessary to open either or both of the valves 34 and 35 to supply the desired amount of fuel vapor to the secondary preheating tubes 20 and 21. Part of the vapor passing through such tubes 20 and 21 will pass to the auxiliary vaporizing burners 40 and 41 and the gas issuing therefrom will be ignited by the flames from the central burner 1 or by any other desired means. The major portion of the gases passing through the auxiliary generating tubes will be mixed with air at the point of entering the mixing chambers and will be fed to the burners 2 and 3 for ordinary consumption. The auxiliary burners 40 and 41 are so positioned as to heat the tubes 20 and 21 to positively vaporize the fuel passing therethrough independently of the heating of the central generating tube 8. 90

It will thus be obvious that I have provided a means for circulating the vaporized gases or fuel into a plurality of generating tubes towards a plurality of burners without first subjecting such gases to be mixed with the air. As a result of this arrangement the gases will not be mixed with the air until they enter the proper mixing chambers when they will properly combine with the desired amount of air to produce a blue flame. There is thus no entrapping or positioning of any of the mixed fuel in a dead end manifold or other place to produce a mixture of variable quality whereby to result in a yellow flame. If it is desired to gradually reduce the flame at the center burner, it is only necessary to move the valve stem 16 inwardly whereby the wire or point 17 gradually closes the orifice in the jet block 10 without a closure of the valve 28. Either one of the burners 2 or 3, or both, may be operated as desired independently of said central burner as the gases passing through tube 12 will enter the auxiliary tubes 13 and 14 and be conducted to the auxiliary generating tubes 20 and 21. The auxiliary burners 40 and 41 will serve as positive vaporizing means in case such a central burner is turned low. 115

Suitable pilot tubes 45 and 46 may be connected to the mixing chamber 4, or mixing chambers 4, 5 and whereby any one or two of the burners may be shut off and reignited as desired. In normal operation of the stove, it will be preferable to have a small 130

flame at the central burner whereby to efficiently vaporize the fuel and to provide a mixture for the pilot tubes 45 and 46, but at no time will such central burner be turned into a blast merely because it is desired to shut off either or both of the auxiliary burners 2 and 3. In other words, instead of circulating the gases at all times in order to obtain a blue flame, I have provided means for circulating the unmixed gases which not only positively provides a blue flame at any or all burners, but which reduces the amount of structure and fuel necessary and which also permits the independent operation of each burner. Due to the size and formation of the main generating tube 8, it will be understood that only a small amount of gas need be fed to and be guided at the central burner to maintain complete vaporization of all fuel fed thereto.

The generating unit, which comprises the head 11 and the main and auxiliary generating tubes, is preferably slideable relative to the mixing chambers whereby said generator unit, when used in connection with a camp stove case, may be moved inwardly together with the fuel container to permit collapsing thereof. Such generating unit is also made movable and slideable relative to the mixing chambers for the reason that in some types of mixing chamber, such a movement will be necessary to effect initial preheating.

Having thus described my invention, what I claim is:

1. A generating unit for a multiple burner structure of the liquid fuel type comprising a main generating member and an auxiliary generating unit, a valve for controlling the fuel supply to said main generating member, a conduit for conducting a portion of the fuel from said main to said auxiliary member, and means for controlling the outlet of a portion of the vapor from said main generating member to a burner without affecting the supplying of vapor to said auxiliary generating unit.

2. A generating unit for a multiple burner structure of the liquid fuel type comprising an integral generating unit having a plurality of vaporizing tubes, a common control for all of said tubes, and independent controls for controlling the outlet of vapor from each of said tubes.

3. A stove structure of the liquid fuel multiple burner type comprising a plurality of burners having independent mixing chambers, and a plurality of generating members adapted to be slidably connected to said mixing chamber.

4. A stove construction of the liquid fuel multiple burner type comprising a plurality of mixing chambers, a generating member adapted to be positioned above one burner and to supply vaporized fuel thereto, a second generator member connected to said

first named generating member, and means for conducting a part of said vaporized fuel to said second generator member.

5. A stove structure of the liquid fuel multiple burner type comprising a plurality of mixing chambers and interconnected generating tubes therefor, a single means for controlling the supply of fuel to all of said generating tubes, and independent means for controlling the discharge of fuel from said generating tubes.

6. A generating unit for stoves of the multiple burner type comprising a head for receiving a main generating tube, and auxiliary generating tubes, said head adapted to receive tubes positioned within said main generating tube for conducting vaporized but unmixed fuel through said head and to said auxiliary generating tubes.

7. A generating unit for stove structures of the multiple burner type comprising a main generating tube, and a burner for heating the same, auxiliary generating tubes having passageways connecting the said main tube and auxiliary vaporizing burners for heating said auxiliary tubes.

8. A stove structure of the multiple burner, liquid fuel type, comprising a plurality of burners, mixing chambers therefor, interconnected generating tubes for each mixing chamber, a liquid fuel supply conduit and means connecting said conduit with one of said tubes for initially conducting all of the fuel therethrough.

9. A stove structure of the liquid fuel multiple burner type comprising a plurality of burners, mixing chambers therefor, interconnected main and auxiliary generating tubes for said mixing chambers, means for controlling the supply of fuel to each of said auxiliary generating tubes from said main generating tube and means for independently controlling the discharge of vaporized fuel from each of said generating tubes.

10. A generating unit for a stove structure of the multiple burner liquid fuel type comprising a central generating tube packed to provide capillary action upon any fuel therein, auxiliary generating tubes, and means positioned within said main generating tube for conducting unmixed fuel or vaporized gases to said auxiliary tubes.

11. A stove structure of the liquid fuel multiple burner type comprising a plurality of burners and mixing chambers therefor, and a plurality of generating members slidably connected relative to said mixing chambers, said generating members being interconnected but independently operable.

12. A stove structure of the liquid fuel multiple burner type comprising a central burner and auxiliary burners and mixing chambers therefor, a generating tube adapted to supply unmixed vaporized gases to

said central mixing chamber, and means for conducting part of said gases from said generating member to a point adjacent said auxiliary burners before being mixed with air to form a combustible mixture.

13. A stove structure of the liquid fuel multiple burner type comprising a plurality of burners, a plurality of mixing chambers and interconnected generating members

therefor, means for permitting independent 10 operation of any burner, and a pilot burner tube connecting with one of said mixing chambers for maintaining a pilot light adjacent one of said burners.

In testimony whereof I affix my signature.

WILLIAM BLASKEWITZ.
